BASEBALL GAMEBOARD

Edward B. Mang, Jr., Ridgewood, N. Y.

Application January 15, 1949, Serial No. 251

Term of patent 7 years

(Cl. D34—5)

To all whom it may concern:

Be it known that I, Edward B. Mang, Jr., a citizen of the United States, residing at Ridgewood, county of Queens, and State of New York, have invented a new, original, and ornamental Design for a Baseball Gameboard of which the following is a specification, reference being had to the accompanying drawing, forming a part hereof.

The figure is a plan view of a baseball gameboard, showing my new design.

The board has been broken away for convenience of illustration.

The board is of conventional thickness.

I claim:

The ornamental design for a baseball gameboard, as shown and described.

EDWARD B. MANG, JR.
